UNITED STATES PATENT OFFICE.

FRANK SCHMITZ, OF CHICAGO, ILLINOIS.

ELASTIC HUB AND AXLE.

SPECIFICATION forming part of Letters Patent No. 663,047, dated December 4, 1900.

Application filed February 19, 1900. Serial No. 5,688. (No model.)

To all whom it may concern:

Be it known that I, FRANK SCHMITZ, a citizen of the United States of America, residing at Chicago, in the county of Cook and State 5 of Illinois, have invented certain new and useful Improvements in Elastic Hubs and Axles, of which the following is a specification.

My invention relates to certain improvements designed especially for use in bicycle 10 hubs and axles, but capable of employment in various other connections.

The object of the invention is to interpose a spring between the hub and axle, mounting the axle so as to give it a limited vertical 15 movement with respect to the hub and guiding it so as to maintain its parallelism therewith.

The invention consists in certain novel 20 characteristics pertaining especially to the arrangement of the parts, so as to provide for suitable adjustment to preserve the latter in easy working relation and also to take up any wear or lost motion.

The invention is illustrated by means of 25 the accompanying drawings, in which—

Figure 1 is a vertical longitudinal section of a hub and portions of the bearings, showing the axle-box in side elevation. Fig. 2 is a similar section, except that the section cuts 30 what will be called the "axle-box" in addition to the parts cut in Fig. 1. Fig. 3 is a plan of the axle and axle-box. Fig. 4 is a horizontal section looking downward from the plane indicated by the line 4 4 of Fig. 2. 35 Fig. 5 is an end elevation of the axle-box, showing the axle in vertical section, as indicated by the line 5 5 of Fig. 3. Fig. 6 is a vertical section in line 6 6 of Fig. 2. Fig. 7 is a face view of a guide-plate. Fig. 8 is a 40 end elevation of the axle-box. Fig. 9 is a similar elevation of one of the guiding-caps arranged upon the end thereof, and Fig. 10 is an end elevation of the axle.

Referring to the drawings, the axle-box A 45 is preferably made of a piece of tool-steel of rectangular cross-section having a depending socket *a*, in which is placed a coiled spring B. The axle-box is longitudinally channeled to receive the axle C and at its 50 ends is slit inward sufficiently to receive vertical guide-legs *c* of the axle and permit the same to play up and down through the axle-

box. The central portion *c'* of the axle is preferably offset upwardly from the end portions *c*² to accommodate a greater length of 55 spring B. Caps D are formed to fit over the ends of the axle-box and are slotted at *d* to allow the axle to play up and down therein and at *d'* *d*² to receive the slit ends of the axle-box. The sides of these caps *d*³ extend 60 toward each other alongside of the axle-box and are guided thereon by means of pins *c*⁴, secured in said box and working in slots *d*⁴ in the caps. The slots *d* *d*² guide the caps upon the ends of the axle-box, and the guide- 65 pins *c*⁴ guide the inner ends of the caps upon the same, preventing oscillation of the end faces of said caps in a vertical plane. Said faces are arranged to bear upon the guide-legs of the axle, and cones E E' are threaded 70 upon the ends of the axle-box and arranged to bear against the caps to adjust the latter toward or from the guide-legs of the axle. Cups F F' are threaded in the hub G, and antifriction-balls H are arranged between the 75 cups and cones.

It should be noticed that the caps may be adjusted to tighten them upon the axle or to loosen them thereon by means of the cones E E', which may also be used to adjust the 80 bearings.

The axle is supported upon the fork of a bicycle or other similar vehicle by means of plates I, which are formed with square bosses *i*, adapted to rest in correspondingly-shaped 85 openings in the fork. The plates are secured upon the ends of the axle, so as to be non-rotatable with respect thereto, means for accomplishing this being shown in the drawings as consisting of pins *i*', passing through 90 the bosses and axle. The ends *c*² of the axle are screw-threaded to receive nuts for securing the axle to the fork.

The inner faces of the plates I are formed with longitudinally-extending ribs *i*², adapted 95 to slide upon the ends of the axle-box A (see Fig. 4) to prevent the latter from turning with the wheel and to guide the axle-box upon the washers. These plates I serve both to close the ends of the axle-box against the 100 admission of dust and to prevent the angular movement of the axle-box with respect to the frame of the machine, the bosses *i* preventing angular movement of the plates with

respect to the frame and the ribs i^2 preventing angular movement of the axle-box with respect to the plates.

Flat springs J are secured upon the ends c^2 5 of the axle-box, which strike upon the inner surface of the cones E E' at the extreme limit of movement of the axle in either direction and prevent any clicking in the operation of the device.

10 The specific details of construction, form, and arrangement herein shown and described, while thought preferable at the present time, are nevertheless capable of considerable modification, and I therefore do not limit myself to the same.

15 I claim as new and desire to secure by Letters Patent—

1. The combination with an axle-box, an axle vertically guided therein having guiding-legs at its opposite ends, of longitudinally-adjustable caps upon the ends of the axle-box and adapted to bear upon said guiding-legs, and a bearing-cone adjustably secured upon the axle-box and capable of longitudinal adjustment thereon to tighten the 25 caps upon the axle; substantially as described.

2. The combination with an axle-box and an axle vertically guided therein having guiding-legs, near its ends, of bearing-cones secured upon the ends of the axle-box and longitudinally adjustable thereon and means adjustable by and with said cones for engaging the guiding-legs of the axle to prevent oscillation of the axle with respect to the axle-box; substantially as described. 30

3. The combination with a channeled axle-box, of an axle guided therein having guide-legs near the opposite ends of the axle-box and caps arranged upon the ends of the axle-box and extending around the sides thereof, said caps being guided both upon the ends and sides of the axle-box and bearing upon the guide-legs of the axle; substantially as described. 35

40 In witness whereof I have hereunto set my hand, at Chicago, in the county of Cook and State of Illinois, this 14th day of February, A. D. 1900.

45 FRANK SCHMITZ.
